UNITED STATES PATENT OFFICE.

FREDERICK W. WILD, JR., OF BALTIMORE, MARYLAND.

POWER-TRANSMITTING DEVICE FOR HAND-DRIVEN MECHANISMS.

SPECIFICATION forming part of Letters Patent No. 708,286, dated September 2, 1902.

Application filed May 6, 1902. Serial No. 106,115. (No model.)

To all whom it may concern:

Be it known that I, FREDERICK W. WILD, Jr., of the city of Baltimore and State of Maryland, have invented certain Improvements in 5 Power-Transmitting Devices for Hand-Driven Machines, of which the following is a specification.

In labeling and other machines which are operated by hand and in which the driving-shaft thereof has to be rotated in one direction only the constant turning of the crank-handle becomes monotonous and irksome, and it is usual for the operator to turn first with one hand and then with the other for 15 relief; but such change affords but a partial relief for the reason that the direction of motion is not altered.

The object of the present invention is therefore the construction of a mechanism which 20 is interposed between the crank-handle and the driving-shaft of the machine or is applied to some driven portion of the machine, whereby the direction of turning of the crank-handle may be reversed without affecting that of the driving-shaft, which will 25 still rotate as before.

In the description of the said invention which follows reference is made to the accompanying drawings, forming a part hereof, and 30 in which—

Figure 1 is an exterior front view of the improved apparatus, and Fig. 2 a central vertical section of the same. Fig. 3 is a section of Fig. 2 taken on the irregular dotted line 35 3 A A and looking in the direction of the straight arrow. Figs. 4, 5, 6, and 7 are details of the mechanism, the last named being on an enlarged scale.

Referring now to the drawings, 1 is a spindle adapted for application to the driving-shaft of the machine to be operated, and it is bored to fit the said driving-shaft, which is not shown. The direction of the rotation of the said spindle when the same is seen from 45 the front of the apparatus in the present case is the reverse of that of the hands of a clock. The bored end of the spindle 1 rotates within a bearing formed in one side of a casting 2, and the other rests loosely within the 50 hub 3 of a spur gear-wheel 4, which hub passes loosely through and is sustained by the side of the said casing.

5 is a crank-handle fastened in any suitable manner to the exposed or outer end of the hub 3 of the spur gear-wheel 4. The inner 55 end of the said hub is bored, and into the cavity thereby formed is forced tightly the ring 7, having the internal ratchet-teeth 9 and the channel 10, which extends entirely through the hub 3 for a purpose hereinafter 60 described. A face view of the wheel 3 is shown in Fig. 4.

Seated loosely in a transverse slot 12 in the spindle 1 is a sliding bolt 13, having its ends beveled in the same direction. This bolt, 65 two views of which on an enlarged scale are shown in Fig. 7, has a length which is slightly less than the distance from the root of one of the ratchet-teeth 9 to the circumference of the spindle diametrically opposite. This construction admits of the one end of the sliding bolt being in contact with the root of one of the ratchet-teeth while its other end is clear 70 of the points of the said teeth. When the crank-handle is turned in the direction indicated by the curved arrow in full lines in Fig. 1, which direction is indicated also by the curved arrow in full lines in Fig. 3, one end of the sliding bolt 13 is forced into locking contact with one of the ratchet-teeth by 75 the inclined surface of another tooth riding over the other end of the said bolt, and the rotary motion of the spur gear-wheel 4 is therefore communicated directly to the spindle through the agency of the sliding bolt 13. 80 Should the crank-handle be turned in the opposite direction, the sliding bolt 13 becomes inoperative and ceases to be a driver, and should no other mechanism be employed the spindle would remain stationary. 85

I will now describe the mechanism whereby in the backward rotation of the crank-handle or that in the direction indicated by the dotted curved arrows in Figs. 1 and 3 the spindle 1 is caused to continue its rotation in 90 the same direction or that before specified.

15 is a fixed shaft secured to the casing 2 in any appropriate manner and preferably by means of screws 16. On this shaft is the loose spur gear-wheel 17, in mesh with the 100 one 4 and also the loose spur gear-wheel 19, which is locked to the one 17 and imparts rotary motion to the corresponding gear-wheel 20, which is loose on the spindle 1, through

the medium of the idle gear-wheel 21, which rotates about the stud 23, projecting inward from the side of the casing 2. The spur gear-wheel 20 is provided with a ring 24 like the one 7, having the ratchet-teeth 25 similar to the ones 9.

27 is a bolt with beveled ends, which like the one 13 slides in a slot in the spindle 1, and its position relatively to the ratchet-teeth 25 within the wheel 20 is the same as that of the one 13 to the teeth 9 within the wheel 4.

Fig. 5 is an exterior view of the spindle 1, showing the slots for the bolts 13 and 27, and Fig. 6 is a cross-section of Fig. 5.

With the construction described when the crank-handle is reversed or moved in the direction indicated by the dotted curved arrows the gear-wheel 20 is caused to rotate in 20 an opposite direction to that of the crank-handle (or in the direction first described with respect to the spindle) through the medium of the sliding bolt 27, the other bolt at the time being inoperative.

25 For convenience in putting together and taking apart the apparatus the casing, which serves to protect the mechanism from dirt, is made in two parts or sections held together by screws, and the said casing is provided with a lug 30, whereby it is supported from some fixed device, which may be a part of the machine to which the apparatus is applied.

The slot 10, before referred to as extending radially from the interior of the hub 3 of 35 the gear-wheel 4 and longitudinally the full length of the hub, including the ring 7, is to allow of the withdrawal of the said wheel from the spindle 1 when the two sections of the casing are separated, the projecting end 40 of the sliding bolt 13 passing through the said channel.

I claim as my invention—

In a power-transmitting mechanism for the purpose described, a spindle which has to be 45 rotated in a certain direction, a gear-wheel loose on the said spindle and to which power is applied, a ratchet mechanism constructed to transmit rotary movement from the said gear-wheel to the spindle when the said gear-wheel is rotated in one direction only, or that to be taken by the spindle, a second gear-wheel loose on the said spindle with ratchet mechanism which in effect is the same as the first, combined with a train of gearing driven 50 from the first gear-wheel, whereby in the reversal in direction of the first gear-wheel, the second gear-wheel is caused to rotate in an opposite direction to that of the first, thereby continuing the rotation of the spindle in 55 the first-described and required direction, substantially as specified.

FREDERICK W. WILD, JR.
